DESIGN FOR A POCKET HANDKERCHIEF

Robert B. Hayden, Seattle, Wash.

Application June 5, 1933, Serial No. 48,284

Term of patent 3½ years

To all whom it may concern:

Be it known that I, ROBERT B. HAYDEN, a citizen of the United States, residing at Seattle, in the county of King and State of Washington, have invented a new, original, and ornamental Design for a Pocket Handkerchief, of which the following is a specification, reference being had to the accompanying drawing, forming a part thereof.

The figure is a plan view of a pocket handkerchief showing my new design.

The shading on the drawing is for the purpose of indicating color.

The pocket handkerchief shown has a different color design on each of the four corners whereby it may be folded to display any selected one of these color designs preparatory to placing it in the breast pocket of a coat.

I claim:

The ornamental design for a pocket handkerchief as shown and described.

ROBERT B. HAYDEN.
